Attorney.

UNITED STATES PATENT OFFICE.

GEORGE WASHINGTON TRAHAN, OF HOUMA, LOUISIANA.

HAND WATER-SPRINKLER.

SPECIFICATION forming part of Letters Patent No. 397,762, dated February 12, 1889.

Application filed October 27, 1888. Serial No. 289,265. (No model.)

To all whom it may concern:

Be it known that I, GEORGE WASHINGTON TRAHAN, a citizen of the United States, and a resident of Houma, in the parish of Terre Bonne and State of Louisiana, have invented 5 certain new and useful Improvements in Hand Water-Sprinklers; and I do hereby declare that the following is a full, clear, and exact description of the invention, which will 10 enable others skilled in the art to which it appertains to make and use the same, reference being had to the accompanying drawings, which form a part of this specification, and in which—

15 My invention relates to certain new and useful improvements in hand water-sprinklers, and relates more especially to such as are designed to be adapted to the use of houses, stores, and offices; and it consists of 20 the parts, as hereinafter more fully set forth and described in the specification and drawings.

The general object of my invention consists in providing a hand-sprinkler adapted 25 for the above purposes with means for regulating and preventing the outward flow of the water from the reservoir at will.

A further object consists in providing a 30 sprinkler simple in its construction, effective in its operation, and more durable than any of a similar kind heretofore known to me.

Referring to the drawings, forming a part 35 of the application, Figure 1 is a perspective view of my improved sprinkler; Fig. 2, a longitudinal vertical section taken on line $x-x$ of Fig. 1; Fig. 3, a detail view of the valve-rod, and Fig. 4 a detail view of the rose.

Like letters of reference are used to 40 designate corresponding parts throughout the entire specification and drawings.

A represents the cylindrical body of the reservoir, the lower end thereof being provided with the external screw-threads, a .

A' indicates the cone-shaped bottom of the 45 reservoir, provided at its top with the internal female screw-threads, a' , so as to permit of the top and bottom of the reservoir being removably secured together. The lower or bottom portion of the cone-shaped bottom A' is 50 provided with the downwardly-extending

screw-threaded flange a^2 , and the same is provided with the central aperture, a^3 .

C is the rose, having the upwardly-extending female screw-threaded projection c , which permits of the same being removably secured 55 to the depending extended portion of the cone-shaped bottom of the reservoir, and provided with the depending flaring portion c' . This flaring portion has a tendency to spread the outward flow of the water from the rose, as 60 well as to protect the apertures therein from clogging with dirt. If desired, the cylindrical body, cone-shaped bottom, and the rose may be soldered or connected one to the other without being removably secured; but by preference I prefer the former mode of connection, 65 as I am enabled thereby to release any part of the sprinkler for the purpose of gaining access thereto for cleaning. I am also enabled, by making the rose removably secured 70 to the reservoir, to permit of a larger or smaller one being secured thereto.

B represents the curved handle or bail of my improved sprinkler secured to the top of the reservoir in any suitable manner, and said 75 bail has the metallic piece b secured (by being riveted, bolted, or otherwise) to its under side, and forming thereby the chamber b' , in which a spring is secured. The metallic plate b is provided with the aperture b^2 , as shown, 80 through which the valve-rod works.

D indicates the valve-rod, the lower end of which has the valve D' secured thereto a short distance from its end. Immediately above the valve, and against which the same 85 impinges, is secured upon the valve-rod the circular collar d . This valve I make, by preference, cone-shaped, so as to permit of the same fitting snugly within the opening formed in the bottom of the reservoir. When the 90 sprinkler is closed against the outward flow of the water, the valve will fit within the aperture a^3 , and is held in place by the pressure of the collar secured to the valve-rod, spring E, and the retained liquid within the reservoir. 95

E represents the spring placed within the chamber b' , the upper end of which is attached to the under side of the bail, forming the top of the chamber, and the lower end is attached to and surrounds the top of the valve-rod D. 100

Of course this spring may be made either flat or spiral.

E' indicates the valve-rod guide secured in any suitable manner within the screw-threaded projection of the cone-shaped bottom of the reservoir, and has formed therein the aperture e, through which the lower end of the valve-rod passes. This aperture forms a guide for the valve-rod in its upward or downward movement.

F is a strainer situated within the upper extended screw-threaded portion of the rose C. The purpose of this strainer is to obstruct the passage of dirt or sediment from the reservoir into the rose, and thereby prevent the clogging of the apertures or perforations f, through which the water is ejected from the same. This strainer may be dispensed with, if desired, or its position may be changed from the rose to the reservoir.

G and G' represent the finger-pieces secured to the valve-rod in any suitable manner, and which are used for the purpose of raising the valve-rod, and with it the valve and collar, from the aperture a³, and allow the flow of water or liquid from the reservoir into the rose, from whence it is ejected through the perforations in the form of a spray.

It is obvious that by constructing a device in accordance with the above description a sprinkler is obtained that may be disconnected at any desired part for cleaning purpose, or from which the rose may be readily removed and a larger or smaller one secured in place thereof, with very little loss of time resulting therefrom, and which will at the same time permit of the liquid being retained within the reservoir during such removal.

Having thus fully described my invention, what I claim as new, and desire to secure protection in by Letters Patent of the United States, is—

1. The combination, in a hand water-sprinkler, of the apertured reservoir, the rose, valve-rod, and valve for controlling the flow of water, the bail having a chamber formed therein, and the spring secured within said chamber and attached to the valve-rod, substantially as and for the purpose set forth and described.

2. In a hand water-sprinkler, the combination of the apertured reservoir consisting of the cylindrical screw-threaded body, and the screw-threaded cone-shaped bottom adapted to be removably secured to the cylindrical body, the rose removably secured to the screw-threaded end of the bottom of the reservoir, the valve-rod, valve, and collar for controlling the outward flow of the liquid from the reservoir to the rose, the valve-rod guide, the spring situated within the chamber formed upon the handle of the reservoir, and the finger-pieces secured upon the valve-rod for raising the valve, collar, and valve-rod, substantially as herein shown and described.

In testimony that I claim the foregoing as my own I have hereunto affixed my signature in presence of two witnesses.

GEORGE WASHINGTON TRAHAN.
